United States Patent Office

Des. 177,564
Patented May 1, 1956

177,564

AIRSHIP

Leonor Zalles Freeland, New York, N. Y.

Application May 6, 1955, Serial No. 35,862

Term of patent 14 years

(Cl. D71—1)

Fig. 2.

Fig. 3.

Figure 1 is a perspective view of an airship embodying my new design;

Fig. 2 is a reduced top plan view of the airship shown in Figure 1; and

Fig. 3 is a reduced bottom plan view of the airship shown in Figure 1.

What is claimed is:

The ornamental design for an airship, as shown.

References Cited in the file of this patent

UNITED STATES PATENTS

D. 173,713	Apostolescu	Dec. 28, 1954
D. 175,873	Apostolescu	Oct. 25, 1955